UNITED STATES PATENT OFFICE.

FREDERICK WILLSON AND NUMA BOURQUIN, OF READING, PENNSYLVANIA.

DESIGN FOR A PAIR OF SPECTACLES.

48,300.

Specification for Design.

Patented Dec. 14, 1915.

Application filed April 21, 1913. Serial No. 762,743. Term of patent 14 years.

To all whom it may concern:

Be it known that we, FREDERICK WILLSON and NUMA BOURQUIN, both citizens of the United States, residing at Reading, in the county of Berks and State of Pennsylvania, have invented a new, original, and ornamental Design for a Pair of Spectacles, of which the following is a specification, reference being had to the accompanying drawing, forming part thereof.

The figure is a perspective view of a pair of spectacles, showing our new design.

We claim:

The ornamental design for a pair of spectacles, as shown.

In testimony whereof we affix our signatures in presence of two witnesses.

FREDERICK WILLSON.
NUMA BOURQUIN.

Witnesses:

D. M. STEWART,
W. G. STEWART.
